CLAIM

The ornamental design for a cart for storing and transporting solid fuels including wood logs and coal, as shown.

DESCRIPTION

FIG. 1 is a front perspective view of a cart for storing and transporting solid fuels including wood logs and coal showing my new design;

FIG. 2 is a front elevational view thereof;

FIG. 3 is a rear elevational view thereof;

FIG. 4 is a side elevational view thereof;

FIG. 5 is an opposite side elevational view thereof; and

FIG. 6 is a top plan view thereof.
